The ornamental design for a winch, as shown and described.

DESCRIPTION

FIG. 1 is a perspective view of a winch showing our new design.

FIG. 2 is a front view thereof.

FIG. 3 is a back view thereof.

FIG. 4 is a right view thereof.

FIG. 5 is left view thereof.

FIG. 6 is a top view thereof; and,

FIG. 7 is a bottom view thereof.

The broken lines shown in the drawings are included for the purpose of illustrating portions of the winch, which form no part of the claimed design.
